(57) **CLAIM**

The ornamental design for a charger for automobile, as shown and described.

DESCRIPTION

FIG. 1 is a perspective view of the front, right side and top plan of a charger for automobile showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom view thereof; and,

FIG. 8 is a perspective view of the charger shown in FIG. 1, shown in the context of usage with an automobile. The automobile, shown in dotted lines, is included for reference only and forms no part of the claimed design.

The portions shown in broken lines are of illustrative purposes only and form no part of the claimed design.
